UNITED STATES PATENT OFFICE.

WILLIAM W. BONNELL, OF BELLEVUE BOROUGH, PENNSYLVANIA.

MEMORANDUM APPARATUS.

1,409,655.

Specification of Letters Patent. Patented Mar. 14, 1922.

Application filed February 7, 1920. Serial No. 357,093.

To all whom it may concern:

Be it known that I, WILLIAM W. BONNELL, a citizen of the United States, and residing in the borough of Bellevue, in the county of Allegheny and State of Pennsylvania, have invented or discovered new, useful, and Improved Memorandum Apparatus, of which the following is a specification.

10. My invention consists in a new and improved memorandum device.

The object which I have in view is the provision of means for registering data or memoranda for household, store, office and similar purposes, whereby the used sheet or portion of paper may be torn off and a fresh sheet moved into its place for the next occasion for use.

For the accomplishment of this object, I 20 provide a mechanism of the following general character. A base consisting of a flat board has journaled at one end and above it a shaft upon which is wound a roll of narrow memorandum paper, the outer or 25 loose end of the roll being led under a keep and over the surface of the base and out under a spring actuated keep which holds the paper flat on the base and which may be retracted to draw the used portion of the 30 paper off of the base. The outer edge of the spring clip forms a knife edge, so that when the memorandum sheet has been drawn off the base, the spring clip may be released to clamp the paper to the base and 35 the used sheet may be given a lateral pull so that it will be detached by cutting along the knife edge. When the spring clip is retracted to permit the drawing off of the used sheet of paper, the end of the paper is 40 exposed to be seized by the fingers. The roll end of the base, which is preferably a wooden strip or narrow board, is preferably provided with a perforation so that the device may be hung on a nail or hook.

45. In the accompanying drawings, Fig. 1 is a side elevation of the device; Fig. 2 is a plan view of the same, and Fig. 3 is a broken perspective showing the spring knife clip thrown up or retracted to permit the paper 50 to be drawn along the base, and also showing the use of a double strip of paper, the under side of the top strip being carbonized to reproduce on the under strip a copy of the data written on the top strip.

The following is a detailed description of the drawings.

A is the base, preferably a narrow wooden board or flat strip of other suitable material, and preferably provided at one end with a hole 1, so that the device may be hung upon the wall.

At one end, the end provided with the hole 1, said base is provided with a pair of opposed standards 2 in which are journaled the ends of the spool shaft 3 upon which is mounted a roll of narrow paper B whose outer end is led down to the base and forward under the metal keep 4 whose ends are fixed to the base and whose body is sufficiently elevated to permit the paper to slide freely along over the base. At the other end of said base are provided a pair of small bearing blocks 5 in which are journaled the ends of the shaft 6, one of whose extremities is bent at an angle to form a handle 7. 8 is a sheet metal knife blade rigidly secured at one edge to the shaft 6, as by wrapping the sheet metal around and soldering it to said shaft. 9 is a spring whose intermediate portion is wrapped around the protruding portion of shaft 6 and whose ends bear respectively against the base A and the handle 7, thus holding the free edge of the blade 8 against the base. The blade 8 extends toward the end of the base away from the roll. The loose end of the paper is, as explained, led under the keep 4 and along the base and under the blade 8, which clamps down on the end of the paper strip.

When data are to be recorded, they are jotted down on the portion of the paper exposed on the base A. If it is desired to remove the memorandum thus made, the blade 8 is retracted or turned up by means of the handle 7 and the end of the paper thus exposed, seized and the paper drawn off the end of the base until the memorandum has passed beyond the blade 8. The handle 7 is then released, allowing the blade to be sprung back into the position for clamping the paper. The portion of paper drawn off the base is then given a lateral jerk, causing it to be cut off by the knife edge. The operation of drawing the paper off the base, of course causes a fresh length of paper to be unwound from the roll and to be drawn onto the base for the next use.

In Fig. 3, I have shown the use of a double strip of paper, the upper strip C and the under strip D, the under surface of the top paper being carbonized so as to make a 5 copy on the lower strip.

It is evident that my invention can be advantageously used for various purposes wherein memoranda must be made and kept.

Thus the housewife may keep the device 10 hanging on the kitchen wall, jotting down items to be ordered from the store; tearing off and destroying the list when the order has been sent in. My memorandum device may also be used in stores for taking orders, 15 and for many other kindred purposes which will suggest themselves.

What I desire to claim is:

1. In a memorandum device of the character described, the combination of a flat 20 board, means for journaling a roll of paper above one end of said board, a keeper traversing said board adjacent to said roll and under which the paper is led, and a second keeper adjacent to the other end of said 25 board under which the paper is also led, said second keeper comprising a shaft journaled transversely of the board and in direct contact with the paper thereon, a blade rigidly secured at one edge to the shaft and adapted to rest at its opposite edge in contact with the paper therebeneath to form a 30 tearing edge, a spring for yieldingly holding the blade in position against the paper on the board, and means for operating the 35 shaft and thereby turning the blade out of contact with the paper while the shaft holds the paper in close association with the board to permit the paper to be drawn out along said board.

40 2. In a memorandum device of the character described, the combination of a flat board, means for journaling a roll of paper

above one end of said board, a keeper traversing said board adjacent to said roll and under which the paper is led, and a 45 second keeper adjacent to the other end of said board under which the paper is also led, said second keeper comprising a pivoted shaft transversely arranged on the board and in direct contact with the paper, a blade 50 rigidly associated with the shaft and adapted to rest at its free edge against the paper to form a tearing edge, means for yieldingly holding the blade in paper contacting position, one end of the shaft constituting a 55 handle for turning the blade out of contact with the paper while the portion of the shaft between its pivotal points holds the paper in close association with the board to permit the paper to be drawn out along said 60 board.

3. In a device of the character described comprising a flat writing surface, a shaft journaled transversely of the surface adjacent one end thereof and adapted to support a roll of paper, keepers arranged transversely of the surface and beneath which the paper is led, one of said keepers consisting of a blade member rigidly secured along one edge to a transversely journaled shaft 70 arranged in direct contact with the paper on the board the opposite edge of said blade adapted to rest against the paper, means for yieldingly holding the blade in position against the paper; and said shaft having an 75 extension at one end thereof to form an operating handle whereby the blade may be lifted while the portion of the shaft between its pivotal points holds the paper in close association with the board to permit the 80 withdrawal of the paper from the roll.

Signed at Pittsburgh, Pa., this 2nd day of February, 1920.

WILLIAM W. BONNELL.
